DRAW ROD ADAPTER

Eugene H. Wagner, Milwaukee, Wis.

Application February 13, 1939, Serial No. 256,049

5 Claims. (Cl. 225—3)

This invention relates to direct draw beer dispensing and cooling cabinets and more particularly to an adapter to accommodate a draw rod for either center or side tapping.

6 The principal purpose and object of my invention is to provide an adapter so constructed and arranged that by merely reversing the relative positions of its parts, the desired passageway out of the cabinet for a draw rod may be easily and 10 quickly provided for either center or side tapping.

In accordance with my invention the adapter comprises a pair of separable block-like elements of the desired material and provided at their engaging surfaces, one with a pair of spaced 15 grooves, and the other with a groove and a projection in the same spaced relation as the grooves in the other element so that the selected grooves may be made to register to provide a draw rod passageway through the adapter while the projection extends into and closes the groove not being used.

Other and further objects of my invention will appear from the following specification taken in conjunction with the accompanying drawing, 25 in which—

Fig. 1 is a fragmentary front elevational view with portions broken away of a direct draw cabinet equipped with a draw rod adapter of my invention;

30 Fig. 2 is a top plan view of the parts shown in Fig. 1;

Fig. 3 is an enlarged vertical sectional view taken on line 3—3 of Fig. 1;

35 Fig. 4 is a perspective view of the adapter with the blocks arranged for side tapping as in Fig. 1; and

Fig. 5 is a similar view of the adapter with the blocks arranged for center tapping.

In the drawing, 1 indicates a combined beer 40 cooling and dispensing cabinet. The latter is constructed to provide one or more keg compartments 2, each being equipped with a door 3 hinged at 4, 4 on the front wall 5 of the cabinet. The doors are mounted to swing outwardly from the 45 cabinet and each door is provided with a latch element 6 to releasably hold the door in closed position. The doors extend close to the bottom wall 7 of the cabinet when the latter is mechanically cooled as shown in Fig. 1. The cooling coil (not shown) for the electrically operated cooling 50 system for the cabinet is located within the cabinet in the space between the keg compartments 2. As this coil is laterally narrow, the keg compartments may be brought relatively close together to reduce the overall length of the cabinet and

provide a narrow panel 8 in the front wall of the cabinet between the doors as shown in Fig. 1.

The cabinet walls are constructed and insulated as required to hold a temperature for cooling the beer in the kegs which are placed in the keg 5 compartments 2 in vertical position on its bottom wall 7 as indicated for the single keg 9 in Fig. 1.

The top of the cabinet is constructed to have a fixed rear bar section 10 and a front drain section 11. The latter, in the cabinet shown, is substantially flush with the rear bar section 10 and comprises two removable drain pans 12, 12, one over each keg compartment. The pans 12, 12 seat on the top of the cabinet as at 13, 14 and meet the rear bar section 10 along its front edge 15 at 15. The supports 13 are at the ends of the cabinet, while the support 14 is at the center of the cabinet at the panel 8.

The adapter 16 of my invention comprises a pair of separable block-like elements 17, 18. The 20 latter have complementary flat engaging surfaces *a*, *b* where they fit together and one block, namely the block 17, is provided in its surface *a* with a pair of spaced semi-cylindrical grooves or recesses 19, 20 extending through the block from top to 25 bottom. The other block element 18 is provided at its flat surface *b* with a semi-cylindrical groove 21 and a similarly shaped projection 22. These parts have the same spacing, size and arrangement as the grooves 19, 20 and register when the 30 block elements are fitted together in the use of the adapter. With the block elements separable, the relative positions of the elements may be reversed to register the grooves 19, 21 for a side tapping or the grooves 20, 21 for a center tapping 35 as shown in Figs. 4 and 5, respectively. In either of these positions, the projection 22 on the block element 18 extends into and closes the groove in the block element 17 not being used for a rod passage. Hence, with the structure shown, the 40 adapter by merely reversing the relative positions of its block elements may be quickly and easily adjusted for either center or side tapping.

The cabinet is equipped with an adapter over 45 each keg compartment 2. The adapter is fitted between the rear bar section 10 and the removable drain pan 12 at the joint between them as shown in Figs. 1 and 2. The block element 17 is fitted to the drain pan 12 at its rear edge, while the block element 18 is fitted to the rear bar section 10 at its front edge. The rear bar section 10 is recessed at 23 to accommodate the adapter and thus allow the front and rear edges of the rear bar section 10 and the drain pans 12 to 50 55

meet at the joint 15 without hinderance by the adapter elements between them.

In the embodiment shown, the block elements have upper and lower flange formations to overlie 5 the top and the bottom surfaces of the rear bar section and the drain pan, respectively. This positions the block elements in the cabinet and also holds them against displacement when in use. The upper and lower flanges on the block 10 17 are marked 24, 24', while 25, 25' indicate similar flanges on the block 18. These flanges project sufficiently from the body portions of the blocks on all sides, except at their engageable surfaces *a*, *b*, and thus span the associated portions 15 of the cabinet which they embrace.

In practice, the block 17 is usually secured to the drain pan 12, fastening members 26 being indicated for that purpose in Fig. 3. Here, the fasteners are in the form of driven members, the 20 frame or body 27 of the drain pan structure being comprised of wood or other material into which headed fasteners may be driven. The block element 18 is not fastened to the rear bar section 10 for it is this element which is rotatable 25 to provide for a side or a center tapping. The flanges on the block 18 hold it in place, and it will be noted in Fig. 2, that the block elements engage at their surfaces *a*, *b* when in use and hence the adapter is held in place without securing the block 18 to any part of the cabinet. With the drain pan removable from the cabinet, the block element 17 is secured to the pan to retain its connection therewith at all times.

The adapter is located in the cabinet with its 35 passage providing grooves disposed for either side or center tapping. This implies that the adapter is disposed with its grooves 19 and 20 eccentrically and centrally arranged with respect to the associated keg compartment 2. Hence, for 40 a side tapping as illustrated in full lines in Fig. 1, the draw rod 28 for the keg 9 extends out of and above the cabinet through the passageway provided by the registering grooves 19, 21. For a keg or barrel with a center bung, the draw rod 45 extends out of the cabinet through the passageway provided on registering the grooves 20, 21. The block 18 is adjusted to provide these passageways, the projection 22 always closing the groove not being used. Hence, the adapter carries 50 its own closure element and the use of a separate plug which may become lost or mislaid is avoided. Moreover, with the closure element a part of the block, the closure may be made to properly fit the grooves in the associated block 55 and thus provide a neat and efficient adapter fixture.

With the block element 18 freely supported by the bar section 10 said block element may be easily and quickly withdrawn from the cabinet 60 on removal of the drain pan 12 for turning the block to reverse its position as desired. The block is thereupon re-inserted into the recess 23 and the drain pan replaced to hold the block in the recess. For a cabinet with a stepped down 65 top design, the block 17 would not have the lower flanges 24'. The blocks may be made of wood or other desired insulation material. If a rubber composition is employed, the blocks would preferably be molded.

70 The draw rod 28 is long enough to reach the bottom of the keg and extend sufficiently above the top of the cabinet to provide the necessary clearance for the beer glasses between the drain pan 12 and the dispensing faucet 29 at the upper 75 end of the rod. The portion of the rod extending

out of the cabinet and within the adapter is sheathed in a tube 30, which may be of rubber or other desired insulating material to hold a temperature for the beer within the rod. The grooves and projection on the adapter blocks have a diameter to accommodate the protecting sheath 30.

The tap fixture for the keg is shown at 31, and which fixture is of the conventional type having a clamp nut 32 and a gas connection 33. 10 For side tapping, the tap is located in the head of the keg close to its chime. For a center tapping, the tap is at the center of the head as indicated in dotted lines in Fig. 1. With my adapter, the cabinet is not limited to one system 15 of tapping, being capable of handling both as herein disclosed. The drain pans when removed open the upper half of the cabinet to the doorways and thus facilitate tapping the kegs, and their insertion into and removal from the cabi- 20 net.

Suitable gaskets or packing (not shown) may be used to seal the joints between the drain pans and associated cabinet parts and also between the adapter blocks and the pan and rear bar 25 sections, respectively. The contacting surfaces *a*, *b* of the adapter blocks are co-extensive and fit sufficiently close to avoid temperature leakage between the blocks. In the cabinet shown, the rear bar section 10 and the drain pans 12 30 35 may be covered with sheet metal 34 and have countersunk form as at 35, 35 for glass holding and draining purposes. The metal coverings may be corrugated at the bottoms of chambers 35, 35 as shown.

The details of construction and arrangement of parts shown and described may be variously changed and modified without departing from the spirit and scope of my invention, except as pointed out in the annexed claims. 40

I claim as my invention:

1. In a direct draw beer dispensing cabinet, the combination with a keg compartment having a top portion consisting of front and rear sections, one of which constitutes a removable drain pan for the cabinet, of an adapter for a draw rod comprising separable block elements disposed between said sections, one of said block elements having a pair of spaced grooves therein and the other block element having a similarly spaced 45 groove and a projection, one of said block elements being reversible with respect to the other block element whereby to register the grooves in the two block elements to provide a draw rod passage between them for either side or center 50 tapping in the respective positions of the block elements and to close by the projection on one block element the groove in the other block element not in use.

2. In a direct draw beer dispensing cabinet, 60 the combination with a keg compartment having a top portion consisting of a fixed bar section and a removable drain pan section, of the adapter for a draw rod comprising separable first and second block elements disposed between said sections, said first block element being secured to the drain pan section and having a pair of spaced grooves therein and the second block element being releasably mounted on the rear bar section and having a groove and a projection in the 65 same spaced relation as the grooves in the first block element, said second block element being reversible with respect to the first block element whereby to register the grooves in the two block elements to provide a draw rod passage between 70 75

them for either side or center tapping in the respective positions of the second block element and to close by the projection on the latter element the groove in the first block element not in use.

5. In a direct draw bar dispensing cabinet, the combination with a keg compartment having a top portion consisting of a fixed bar section and a removable drain pan section, of an adapter for 10 a draw rod comprising separable block elements disposed between said sections, one of said block elements having a pair of spaced grooves therein and the other block element having a similarly spaced groove and a projection, one of said block 15 elements being reversible with respect to the other block element whereby to register the grooves in the two block elements to provide a draw rod passage between them for either side or center tapping in the respective positions of the block elements and to close by the projection on one block element the groove in the other block 20 element not in use, said block elements having flange formations in overlapping relation with the fixed bar and removable drain pan sections, 25 respectively.

4. In a direct draw bar dispensing cabinet, the combination with a keg compartment having a top portion consisting of a fixed bar section and a removable drain pan section, of an adapter for 30 a draw rod comprising separable block elements disposed between said sections, one of said block

elements having a pair of spaced grooves therein and the other block element having a similarly spaced groove and a projection, one of said block elements being reversible with respect to the other block element whereby to register the 5 grooves in the two block elements to provide a draw rod passage between them for either side or center tapping in the respective portions of the block elements and to close by the projection on one block element the groove in the other 10 block element not in use, said bar and drain pan sections being disposed with their opposed edges in juxtaposition with a recess in the edge of one of them to accommodate the block elements.

5. An adapter of the character and for the purpose described, comprising a block-like unit divided longitudinally into separable block elements, one having a pair of spaced grooves therein and the other having a similarly arranged groove and a projection, said grooves and 15 said projection extending transversely across the elements between the ends thereof at their meeting surfaces and said block elements being reversible one with respect to the other so to register the grooves in the two block elements to provide a draw row passage between them for either 20 side or center tapping in the respective positions of the block elements and to close by the projection on one block element the groove in the other block element not in use. 25
